CLAIM

I claim the ornamental design for an ergonomic small animal waste removal tool, as shown and described.

DESCRIPTION

FIG. 1 is a top plan view of an ergonomic small animal waste removal tool in accordance with the present design; FIG. 2 is a front view thereof; FIG. 3 is a rear view thereof; FIG. 4 is bottom view thereof; FIG. 5 is a side, rear perspective view thereof;

(Continued)

FIG. 6 is a side elevation view thereof; and,
FIG. 7 is an opposite side elevation view thereof.
